CLAIM

I claim the ornamental design for a condom with a spiraled wall, as shown and described.

DESCRIPTION

FIG. 1 is a view of the condom with a spiraled wall according to the design;

FIG. 2 is a view of the opposite side of the design, relative to the view of FIG. 1;

FIG. 3 is a view of the right side of the design, relative to the view of FIG. 1;

FIG. 4 is a view of the left side of the design, relative to the view of FIG. 1;

FIG. 5 is a top view of the design; and,

FIG. 6 is a bottom view of the design.
